United States Patent Office

Des. 180,530
Patented June 25, 1957

180,530

PORTFOLIO OR SIMILAR ARTICLE

Milton D. Sherman, Brooklyn, N. Y.

Application July 11, 1956, Serial No. 42,211

Term of patent 14 years

(Cl. D87—5)

Fig. 1

Fig. 2

The dot and dash line showing of a brief case in Figure 1 is for illustrative purposes only.

I claim:

The ornamental design for a portfolio or similar article, as shown and described.
